UNITED STATES PATENT OFFICE.

SYDNEY EUSTACE TOMBLESON, OF KENNINGTON PARK, ENGLAND.

JUG.

No. 903,026.

Specification of Letters Patent.

Patented Nov. 3, 1908.

Application filed November 8, 1907. Serial No. 401,335.

To all whom it may concern:

Be it known that I, SYDNEY EUSTACE TOMBLESON, a subject of the King of Great Britain, of 10 Cranworth Gardens, Kennington Park, in the county of Surrey, England, have invented a new and useful Improvement in Jugs or other Receptacles of the Like Kind for Liquids, of which the following is a specification.

10 This invention relates to jugs, or other receptacles of the like kind, for liquids, and has more particular reference to that class of receptacle or apparatus intended to contain two or more liquids which can be poured therefrom simultaneously.

Such receptacles or apparatus as hitherto constructed and employed for effervescent beverages, have comprised two or more vessels combined together, or one vessel divided 20 into two or more compartments, each being furnished with a spout but having a common point of delivery, so that in use the liquids flowing therefrom were mingled and fell together into the cup, glass, or other vessel.

25 My present invention has for its object a duplex jug, or vessel of the like kind, consisting of two separate parts having flat sides fitting against each other so that when fitted together they resemble in appearance an ordinary jug, but if the two separate parts are filled with different liquids, the liquid from either part can be poured out independently of the other, or the liquids can be poured out from both jugs simultaneously.

35 The accompanying drawing is in illustration of my invention:—Figure 1 being a side elevation of a jug embodying my improvements applied to a coffee and milk jug, and showing the pivoted part, or receptacle, in a vertical plane, and the fixed part, or receptacle, tilted as in use for pouring out its contents. Fig. 2 is a central vertical section, at right angles to Fig. 1 illustrating both receptacles in their normal position.

45 In order to put my invention in operation, and as illustrated, I make of metal, earthenware, glass, or other suitable material, a jug *a* divided into two parts by a vertical plane passing down the center, each part *a'*, *a''* having a flat side *b* adjoining the dividing line, so that when these two flat sides *b*, *b* are fitted against each other, they resemble more or less in appearance an ordinary jug, but each half forming an entirely separate vessel. The foot *c* of the jug is, on the other

hand, formed, or attached to, as shown, one part *a'* only of the jug, while the spout is formed in two parts *d*, *d'* (Fig. 1) each constituting a distinct and separate spout.

The handle *e*, however, which may be of the usual or other shape, is attached to (as illustrated)—or forms part of—one only of the two halves *a'* of the jug *a*.

I use preferably a frame or stand upon which the jug made as described stands, and upon this stand or upon the foot *c* itself, I make and fix an upright bracket or support *f*, to the upper end of which is freely pivoted the half *a''* of the jug *a* which is without the handle or the foot.

In the drawing I have shown the pivoted part *a''* carried in bearings *f'*, *f''* respectively formed at the upper end of one of the arms of the bracket *f* and in the flat side of the fixed receptacle *a'* (Fig. 2). The pivot is situated somewhat above the center of gravity of the half *a''* of the jug *a* which is pivoted to it, and the bracket *f* may be suitably bent or shaped to strongly support the pivoted part *a''*.

The body of the jug may be of any suitable shape, more or less spherical, (as shown), or having flat sides, the outer ones parallel with the flat sides *b*, *b* which fit against each other as described.

In a jug made in two halves as described the different contents of the two halves *a'*, *a''* can be poured out either simultaneously or separately as desired, by the ordinary act of pouring out as from a jug of the usual shape, which it resembles in appearance when not in use.

In the drawing, *g* is a projection or knob fixed upon the pivoted part *a''* against which one of the fingers can be pressed when it is desired to pour out the contents simultaneously, and in which case the jug bears the ordinary appearance.

h, *h'* are hinged lids fitted respectively to the fixed and pivoted parts *a'*, *a''*.

The details of construction and shape may be varied more or less as may be found advisable.

What I claim as my invention and desire to secure by Letters Patent, is:—

1. The combination in a jug, or receptacle for liquids, of two separate vessels having flat sides fitting against each other, one of the parts being pivoted between the adjoining flat side of the other part and a bracket

expanding upwardly from a support rigid with the other part upon which the jug is adapted to stand when not in use, a separate spout to each part, a handle formed upon or attached to the fixed part, and a knob or projection on the pivoted part for use when it is desired to pour out from both vessels simultaneously as set forth.

2. The combination in a jug, or receptacle for liquids of a supporting base having brackets, two separate vessels having flat sides fitting against each other and a pivotal connection between them, the outer sides of the vessels engaging the brackets, the pivotal connection and the bracket engaging the outside of one of the vessels, permitting independent or simultaneous use of the vessels.
3. In combination, a base formed with brackets, two vessels having flat sides abutting against each other, means for mounting the vessels to permit one to be tilted to pour

liquid therefrom independent of the other or both to be tilted simultaneously.

4. In combination, two vessels having flat sides which abut against each other, a journal attached to one of said vessels, means located above the center of the vessels adjacent the flat sides and in alignment with the journal for pivotally connecting said vessels together, a base having two upwardly extending brackets one of which is provided with a bearing to receive the journal on the vessel, means for securing the opposite vessel to the base and opposite bracket, and a handle on the vessel which is secured to the base.

In witness whereof I have hereunto set my hand in the presence of two witnesses.

SYDNEY EUSTACE TOMBLESON,

Witnesses:

ARTHUR E. EDWARDS,
D. K. BOYLE.
